UNITED STATES PATENT OFFICE

115,309

DESIGN FOR A HOE

John M. Council, Wananish, N. C.

Application April 26, 1939, Serial No. 84,585

Term of patent 14 years

To all whom it may concern:

Be it known that I, John M. Council, a citizen of the United States and a resident of Wananish, in the county of Columbus and State of North Carolina, have invented the new, original, and ornamental Design for a Hoe of which the following is a specification.

Reference is had to the accompanying drawing forming part thereof, in which:

I claim:

The ornamental design for a hoe, as shown.

JOHN M. COUNCIL.
